(57) **CLAIM**

The ornamental design for a card box as shown and described.

DESCRIPTION

FIG. 1 is a raised perspective view of a first embodiment of a card box shown in an environment of use;

FIG. 2 is a top view of the first embodiment;

FIG. 3 is a bottom view of the first embodiment;

FIG. 4 is a front view of the first embodiment;

FIG. 5 is a right side view of the first embodiment;

FIG. 6 is a raised perspective view of a second embodiment of a card box shown in an environment of use;

FIG. 7 is a top view of the second embodiment;

FIG. 8 is a bottom view of the second embodiment;

FIG. 9 is a front view of the second embodiment; and,

FIG. 10 is a right side view of the second embodiment.

The left side view is a mirror image of the right side view for each embodiment.

The rear view is a mirror image of the front view for each embodiment.

The broken lines showing a card case in FIG. 1 and FIG. 6 illustrate environmental subject matter only and form no part of the claimed design. All other broken lines in the drawings illustrate portions of the card box which form no part of the claimed design.
